UNITED STATES PATENT OFFICE.

WILLIAM A. STARK, OF TACOMA, WASHINGTON.

MELON-CARRIER.

No. 882,722.

Specification of Letters Patent. Patented March 24, 1908.

Application filed December 16, 1907. Serial No. 406,778.

To all whom it may concern:

Be it known that I, WILLIAM A. STARK, a citizen of the United States, residing at Tacoma, in the county of Pierce and State of Washington, have invented certain new and useful Improvements in Melon-Carriers, of which the following is a specification.

This invention is a melon carrier, and particularly one for carrying watermelons.

10 The object of the invention is to provide a carrier which can be adjusted according to the size of the melon, and also one which is simple in construction, and which can be readily applied to and removed from the 15 melon.

In the accompanying drawing, Figure 1 is a perspective view of the invention showing the application thereof, and Fig. 2 is a plan view showing the carrier removed from the 20 melon.

Referring specifically to the drawing, 5 denotes the handle of the carrier which is a piece of wire bent into a loop to form said handle. Near each end of the loop the wire 25 is bent outwardly, and the two branches 6, thus formed, are curved to fit the outside surface of the melon. The branches are divergent and of such a length so as to extend partly around the melon. At the extremity 30 of the branches the wire is bent to form eyes 7 and 8, respectively, and from the eye 7, the wire is bent inwardly to form a cross-bar 9, the end of the wire being secured to the opposite eye 8 by twisting it as shown, or in any 35 other suitable manner.

To the eye 8 is tied or otherwise made fast, a cord 10 which passes through the kerf 11 of a clamp 12 having the form of an ordinary wooden clothes-pin. At the free end of the 40 cord is a knot 13 to prevent withdrawal thereof from the kerf. A cord 14 is tied or otherwise secured to the eye 7, and also passes through the kerf 11. There is a trans-

verse pin 15 in the kerf to prevent the two cords from slipping out of the same. The 15 cord 14 is longer than the cord 10, and has at its free end a knot 16 to prevent unraveling. There is also a knot 17 in the cord 14 on the same side as the knot 13, whereby the clamp 12 is held in proper position. 50

The holder is applied as follows: The wire portion is placed in front of the person with the handle 5 outwardly presented and the melon is placed on the branches 6. The cords are then passed around the melon, the cord 14 being wrapped once or twice around the branches 6 adjacent the handle. The cord is then brought to the clamp and passed through the kerf 11. It is then passed under the clamp over the cords and pulled tight and brought back to the kerf and passed therethrough once or twice. With the parts in this position, the melon will be securely held and can be easily carried by taking hold of the handle 5. The carrier can be quickly 60 removed, it can be readily adjusted to fit different sized melons, and by reason of its simplicity of construction it can be cheaply produced. 65

I claim:—

70 A melon carrier comprising a handle, a pair of arms extending therefrom, a kerfed clamping-member, a transverse pin in the kerf, cords connected at one end to the arms, respectively, and passing through the kerf between its inner end and the aforesaid pin, one of said cords being connected to the clamping-member, and the other cord being of greater length than said cord and extending beyond the clamping-member. 75 80

In testimony whereof I affix my signature, in presence of two witnesses.

WILLIAM A. STARK.
